UNITED STATES PATENT OFFICE.

JOSEPH NEWTON COPELAND, OF ALTOONA, ALABAMA, ASSIGNOR TO J. N. RICKLES, OF ALTOONA, ALABAMA.

PICTURE-HANGER.

No. 893,788.

Specification of Letters Patent.

Patented July 21, 1908.

Application filed June 15, 1906. Serial No. 321,891.

To all whom it may concern:

Be it known that I, JOSEPH NEWTON COPELAND, a citizen of the United States, residing at Altoona, in the county of Etowah and 5 State of Alabama, have invented a new and useful Picture-Hanger, of which the following is a specification.

The invention relates to improvements in picture hangers.

- 10 The object of the present invention is to improve the construction of picture hangers, and to provide a simple, inexpensive and efficient device adapted to be readily applied to a picture, and capable of enabling the same 15 to be readily hung from a nail, or from a molding and of effectually preventing a picture from being accidentally knocked down, when suspended from a nail, screw or similar supporting device.
- 20 A further object of the invention is to provide a picture hanger of this character, which will enable the angle or inclination of a picture to be readily changed, and which will obviate the necessity of providing a shelf, or 25 other means for supporting the lower edge of a picture.

With these and other objects in view, the invention consists in the construction and novel combination of parts hereinafter fully 30 described, illustrated in the accompanying drawing, and pointed out in the claims hereto appended; it being understood that various changes in the form, proportion, size and minor details of construction, within the 35 scope of the claims, may be resorted to without departing from the spirit or sacrificing any of the advantages of the invention.

In the drawing:—Figure 1 is a side elevation of a picture provided with a picture 40 hanger, constructed in accordance with this invention. Fig. 2 is an enlarged longitudinal sectional view, illustrating the construction of the device for adjustably supporting the chain, which is connected with the picture. 45 Fig. 3 is a perspective view of the same. Fig. 4 is a detail view of the brace, which is connected with the bottom of the picture. Fig. 5 is a detail sectional view on the line 5—5 of Fig. 2.

50 Like numerals of reference designate corresponding parts in all the figures of the drawing.

1 designates a chain, connected at its upper end with the center of the top of a picture 55 frame 2 by means of a screw eye 3, or other

suitable fastening device, and secured at its lower end to an approximately inverted V-shaped brace 4. The chain is preferably provided at its upper end with a hook 5 for engaging the screw eye 3, and the bill of the hook is adapted to be bent inward toward the shank of the hook for confining the screw eye to prevent the chain from becoming disengaged therefrom.

The chain, which constitutes a picture 65 cord, is adjustably supported at an intermediate point by the means hereinafter described, and it consists of a lower vertical portion extending downwardly from the supporting means, and an inclined top portion 70 extending outwardly from the supporting means, the two portions being adapted to have their relative length varied by the movement of the picture cord through the supporting means to change the inclination 75 of a picture.

The brace, which is preferably constructed of wire, consists of inclined sides connected together at their upper ends, and having their lower or outer portions 6 bent horizontally to form pivots or pintles, which are arranged in bearing eyes 7 of the plate or leaves 8. The wire, of which the brace is constructed, is bent at the upper ends of the inclined sides to form an eye ring 4^a, and it is 80 twisted at the bottom thereof. The lower end of the chain is preferably provided with a hook 1^a, which is linked into the eye 4^a, and which is preferably closed to secure it in engagement with the same. The terminals 85 of the wire, of which the brace is constructed, are bent at an angle to retain the pivots in the eyes of the plates or leaves, which are 90 secure to the bottom of the picture frame at the corners thereof, whereby the brace is 95 hinged to the picture frame, and is adapted to adjust itself to the position of the same.

The chain passes over a sprocket wheel 9, and the links of the chain mesh with the sprocket teeth of the wheel, which is centrally journaled in suitable bearings 10 of a slide 11. The sprocket wheel is provided with suitable journals, preferably formed by a shaft or pin, which pass through a central opening of the sprocket wheel. The slide 11, 100 which is constructed of sheet metal, or other suitable material, is bifurcated or cut away at its lower portions to provide a recess for the reception of the sprocket wheel, and the sides of the slide are bent or rolled upon 110

themselves to form longitudinal openings 12 for the reception of parallel side portions 13 of a hanger frame. The slide is adapted to move upward and downward on the hanger frame, which consists of a wire body portion 5 and a top connecting plate 14, which has its side edges rolled to form beads 15 for the reception of upper ends of the sides of the wire body portion of the hanger frame. The 10 wire body portion is composed of two sides, which are secured at their upper terminals in the beads 15 of the connecting plate, and which are connected at their lower ends by a transverse bar or portion 16. The lower 15 portions of the sides are bent rearwardly to form projecting arms 17, which are approximately U-shaped. These arms are adapted to fit against the wall, as clearly illustrated in Fig. 1 of the drawing, for off-setting the 20 sprocket wheel and the chain therefrom, so that the sprocket wheel will rotate freely when it is unlocked, as hereinafter fully explained. The parallel guiding portions 13 of the hanger frame are also off-set from the 25 wall by the arm 17 and by upper intermediate bends 18, and the slide is movable upwardly and downwardly on the said guiding portions 13 to carry the sprocket wheel into and out of engagement with the bottom 30 transverse connecting bar or portion 16. When the sprocket wheel is subjected to the weight of the picture, two of its teeth are caused to straddle the transverse bar or portion 16, whereby the sprocket wheel is 35 interlocked with the hanger frame and is held against rotary movement.

The slide is automatically moved upwardly by a coiled spring 19 to disengage it from the hanger frame, when it is relieved of the 40 weight of the picture. The coiled spring is located between the sides of the hanger frame and its lower end is secured to the top of the slide in a perforation 20 thereof, and when the sprocket wheel is lifted out of engagement with the bottom of the hanger frame by the spring, the said sprocket wheel is adapted to rotate freely to permit the picture to be tilted to any angle or inclination. As soon as the picture is adjusted to 45 the desired angle or inclination, its weight will move the slide downwardly and carry the sprocket wheel into engagement with the transverse bar or portion of the hanger frame.

50 The upper end of the spring 19 is connected with one arm of an approximately L-shaped latch 21, which is fulcrumed at its angle and which is adapted to lock the hanger frame in engagement with a nail or screw. The latch 21 is provided at its 55 angle with laterally projecting pivots 22, and it has an inwardly or rearwardly extending arm 23, which is provided with a perforation into which the upper end 24 of the spring is hooked. The pivots 22 are

arranged in suitable bearings of ears or flanges 25, which are formed integral with the connecting plate 14 and which extends outwardly therefrom at the lower end thereof. The other arm of the latch extends upwardly and is provided at the top with an inwardly bent lip or portion 26.

The upper portion of the connecting plate 14 is provided with a key hole slot 27 having its enlarged portion or entrance opening 28 at the bottom to enable the head of a nail or screw to be passed through the slot. The lip or flange of the latch is held against the connecting plate 14 by the spring 19, and it covers the lower enlarged portion 28 of the 70 slot 27, and when the nail or screw is arranged in the upper portion of the slot 27, the latch will lock the same in such upper portion and effectually prevent the picture from being accidentally knocked down.

The hanger frame is provided at the top with a wire molding hook 29, composed of two sides provided at their lower terminals with eyes 30, which are linked into perforations of the upper end of the plate 14. The 90 hook 29 is adapted to engage a molding strip 31, as clearly shown in Fig. 1 of the drawing, and the picture hanger may be hung with equal facility from either a picture molding or a nail or screw.

95 It will be seen that the picture hanger is exceedingly simple and inexpensive in construction; that it is easily operated to arrange a picture at the desired angle or inclination, and that the picture is automatically locked at any adjustment, when the picture hanger is subjected to the weight of the picture.

Having thus fully described my invention, what I claim as new and desire to secure by 105 Letters Patent, is:—

1. A picture hanger comprising a hanger frame, a centrally journaled sprocket wheel mounted on the frame, and a picture cord having a chain passed at an intermediate 110 point partially around the wheel and having one end extended to the top and the other end to the bottom of the picture frame, said picture cord being movable over the sprocket wheel to change the inclination of the picture frame, and means carried by the hanger frame for automatically locking the wheel against rotary movement when subjected to the weight of the picture frame.

2. A picture hanger comprising a hanger 120 frame, a centrally journaled sprocket wheel slidably mounted on the hanger frame to carry its teeth into and out of engagement with the said frame to lock and release the sprocket wheel, and a picture cord consisting 125 of a sprocket chain intermediately supported by and meshing with the sprocket wheel and provided at its ends with means for attaching it to the top and bottom of a picture frame, said picture cord being composed of a 130

substantially vertical lower portion extending downwardly from the hanger frame, and an upper portion extending outwardly from the hanger frame, and yieldable means for carrying the sprocket wheel out of engagement with the hanger frame when the chain is relieved of the weight of the picture frame.

3. A picture hanger comprising a hanger frame, and a picture cord supported at an intermediate point by the hanger frame and consisting of an upper outwardly extending portion provided with means for attaching it to the top of a picture frame, and a lower substantially vertical portion extending downwardly from the hanger frame, and a substantially V-shaped brace centrally secured to the lower end of the picture cord and provided at its ends with means for pivotally connecting it to the bottom of the picture frame at opposite sides thereof.

4. A picture hanger comprising a flexible connection provided at its ends with means for securing it to a picture frame at the top and bottom thereof and shiftable longitudinally to change the inclination of the said picture frame, a hanger frame provided with yieldable means receiving the flexible connection at an intermediate point and operated by the weight of the picture to lock the flexible connection, said means being adapted to automatically release the flexible connection when relieved of the weight of the picture.

5. A picture hanger comprising a flexible connection having means for suspending a picture frame from it and shiftable longitudinally to change the inclination of the same, a hanger frame, and a yieldably mounted rotary device carried by the hanger frame and receiving the flexible connection at a point intermediate of the ends thereof and operated by the weight of the picture to lock it against movement, said rotary device being automatically released when relieved of the weight of the picture.

6. A picture hanger comprising a chain having means for suspending a picture frame from its ends and shiftable longitudinally to change the inclination of the picture frame, a hanger frame, and a yieldably mounted sprocket wheel receiving the chain at a point between the ends thereof and being movable into engagement with the hanger frame by the weight of the picture, whereby the said sprocket wheel is locked against rotary movement, said sprocket wheel being automatically moved out of such engagement when relieved of the weight of the picture.

7. A picture hanger comprising a chain having means for suspending a picture frame from its ends and shiftable longitudinally to change the inclination of the picture frame, a hanger frame, a sprocket wheel slidable on the hanger frame and receiving the chain, said hanger frame being provided with

means arranged to interlock with the sprocket wheel, and means for moving the sprocket wheel out of such engagement.

8. A picture hanger comprising a chain having means for suspending a picture frame from its ends and shiftable longitudinally to change the inclination of the picture frame, a hanger frame, a sprocket wheel mounted on the hanger frame and movable into and out of engagement with the same and receiving the chain, and a spring for automatically moving the sprocket wheel out of engagement with the hanger frame.

9. A picture hanger comprising a chain having means for suspending a picture frame from its ends and shiftable longitudinally to change the inclination of the picture frame, a hanger frame, a slide mounted on the hanger frame, a sprocket wheel carried by the slide and receiving the chain and movable into engagement with the hanger frame by the weight of the picture, and a spring for moving the sprocket wheel out of engagement with the hanger frame when relieved of the weight of the picture.

10. A picture hanger comprising a hanger frame provided with a cross piece having projecting arms, a slide mounted on the hanger frame, a sprocket wheel carried by the slide and arranged to engage the said cross piece, a chain arranged on the sprocket wheel having means for connecting it with a picture, and a spring connected with the slide for moving the sprocket wheel out of engagement with the cross piece when it is relieved of the weight of the picture.

11. A picture hanger provided with a slot having an enlarged portion to permit the head of a screw or nail to pass through it, and a spring actuated latch arranged to cover the enlarged portion of the slot to confine the nail or screw in the other portion of the same.

12. A picture hanger provided with a slot having an enlarged portion, a substantially L-shaped latch pivoted at its angle to the picture hanger and provided at one of its arms with a lip arranged to cover the enlarged portion of the slot, and a spring connected with the other arm of the latch.

13. A picture hanger comprising a hanger frame having a slot to receive a supporting device, a rotary member slidable on the frame, locking means mounted on the frame and arranged to hold the same in engagement with the said supporting device, a flexible connection arranged on the rotary member and provided with means for connecting it with a picture, whereby the weight of the picture will carry the rotary member into engagement with the frame, and a spring for moving the rotary member out of engagement with the frame, when relieved of the weight of the picture frame, said spring being connected with the locking means.

14. A picture hanger comprising a hanger frame, a sprocket wheel slidably connected with the hanger frame and arranged to engage the same, a flexible connection arranged 5 on the sprocket wheel and adapted to be secured to a picture, a latch pivotally mounted on the hanger frame, and a spring for moving the sprocket wheel out of engagement with the frame when relieved of 10 the weight of the picture frame, said spring being connected with the latch and adapted to be placed under tension by the weight of a picture.
15. A picture hanger comprising a hanger frame, a picture cord supported at an intermediate point by the hanger frame and movable through the same and provided at its ends with means for connecting it with the top and bottom of a picture frame, and a 20 movable locking device operable by the weight of the picture frame for engaging the picture cord to secure the same in its adjustment.
16. A picture hanger comprising a hanger frame having a slot to receive a supporting device, a slide mounted on the hanger frame, a rotary member carried by the slide, locking means mounted on the frame and ar-

ranged to hold the same in engagement with the supporting device, a flexible connection 30 arranged on the rotary member and provided with means for suspending a picture from it, whereby the weight of the picture will carry the rotary member into engagement with the frame, and a spring connected 35 with the rotary member and with the locking means.

17. A picture hanger comprising a hanger frame, a slide mounted thereon, a sprocket wheel carried by the slide and arranged to 40 engage the hanger frame, a flexible connection arranged on the sprocket wheel and provided with means for suspending a picture from it, a latch pivotally mounted on the hanger frame, and a spring connected with 45 the latch and with the slide and adapted to be placed under tension by the weight of a picture.

In testimony, that I claim the foregoing as my own, I have hereto affixed my signature in 50 the presence of two witnesses.

JOSEPH NEWTON COPELAND.
